UNITED STATES PATENT OFFICE.

MAX MAURAN, OF NIAGARA FALLS, NEW YORK, ASSIGNOR TO THE
MATHIESON ALKALI WORKS, OF VIRGINIA.

DESIGN FOR A CARBON ANODE.

SPECIFICATION forming part of Design No. 34,277, dated March 26, 1901.

Application filed January 10, 1901. Serial No. 42,812. Term of patent 14 years.

To all whom it may concern:

Be it known that I, MAX MAURAN, mechanical engineer, residing at Niagara Falls, in the county of Niagara and State of New York, have invented and produced a new, useful, and original Design for the following article of manufacture—to wit, Carbon Anodes—of which the following is a specification thereof, accompanied by drawings, which show the new design or configuration.

In the drawings, Figure 1 is a perspective view of an anode, showing the new design. Fig. 2 is a plan view of the same. Fig. 3 is a bottom view of the same.

The leading or material features of the design consist in the inverted-T shape, with a shank *s* and flanges *f*. The flanges spring from the opposite sides of the shank through-

out the whole length of the longest dimension of the shank, as shown. The cross-section is the same throughout the entire length. The lower face of the anode is formed by the two flanges and the base of the shank is substantially flat.

Having now described my invention, what I claim as new, and desire to secure by Letters Patent, is—

The design for a carbon anode as herein shown and described.

Signed this 30th day of November, 1900, at Niagara Falls, New York.

MAX MAURAN.
